UNITED STATES PATENT OFFICE.

RALPH C. BRONSON, OF CHICAGO, ILLINOIS, ASSIGNOR TO MULTIPLE ELECTRIC COMPANY, OF CHICAGO, ILLINOIS, A CORPORATION OF ILLINOIS.

FUSE-PLUG.

1,396,352.

Specification of Letters Patent.

Patented Nov. 8, 1921.

Application filed April 2, 1917. Serial No. 159,055.

To all whom it may concern:

Be it known that I, RALPH C. BRONSON, a citizen of the United States, residing at Chicago, in the county of Cook and State of Illinois, have invented a certain new and useful Improvement in Fuse-Plugs, of which the following is a specification.

This invention relates to electric fuse plugs for electric circuits and has for its object to provide a new and improved fuse plug having a plurality of pieces of fuse metal arranged so that they can be successively used, the plug being further arranged so as to prevent any injury or bad effect from the blowing of the pieces of fuse metal. The invention is illustrated in the accompanying drawings wherein—

Figure 1 is a view showing a plug embodying the invention.

Fig. 2 is a sectional view taken on line 2—2 of Fig. 1, with the holes for the fuse metal unfilled.

Fig. 3 is a sectional view similar to Fig. 2 except that it is taken at an angle of 90 degrees from the section of Fig. 2, with the holes for the fuse metal filled.

Fig. 4 is an enlarged top view of the fuse holding section.

Fig. 5 is a view showing one form of fuse metal piece used in the plug.

Like numerals refer to like parts throughout the several figures.

In carrying out my invention I provide a fuse plug of suitable insulating material divided into two sections, 1 and 2, the sections being separable, that is, the section 2 being a removable section. Connected with the section 1 is an outer metallic piece 3 which acts as one terminal of the socket and must be constructed to serve this purpose, and for purposes of illustration I have shown it as a sleeve. The section 2 is arranged so that it may be inserted into the socket in which the plug is threaded. This metal piece is connected with the part 1 in any desired manner. In the construction shown the metal piece 3 is provided with the projections 3^a which extend through openings in the part 1. On the outer face of the part 1 are small recesses 3^b into which the ends of the part 3^a project and which are filled with solder or the like to fasten the part 3^a to the part 1. The removable section 2 may be removed from the metal piece 3 but is normally held

in position therein. The section 2 is held out to receive a series of pieces of fuse metal, and for purposes of illustration I have shown a plurality of fuse receiving holes or openings 4 each adapted to receive a piece of fuse metal 5. After the pieces of fuse metal are placed in position some non-combustible material 10 is inserted in the section 2 such as plaster Paris cement or the like and which hardens and holds the pieces of fuse metal in place, and at the same time prevents any bad effect from the blowing of the fuse such as the flying out of sparks, heated particles or the like. This material 10 is preferably such that it can be poured in liquid form and will then harden, although it may be applied in any other manner which will produce a hardened core surrounding the or embedding the pieces of fuse material. These pieces of fuse metal are electrically connected at the lower end to a central part 6 or washer which acts as a contact for the plug and which engages a suitable contact in the socket so as to connect any one of the fuse metal pieces 5 in circuit. This washer is preferably provided with a series of projections 6^a which project into the openings 4 and engage the pieces of fuse metal 5, the ends thereof being also embedded in the material 10. When the fuse is blown, the fuse metal will melt intermediate the points where 6^a and 9^a contact the fuse metal and hence the action will all be within the core of material 10. The pieces of fuse metal are preferably longer than the section 2 or at least are of such length that the ends thereof may project beyond said section and the section 1 is preferably provided with receiving openings 7 for receiving these ends. The metal piece 3 which acts as one of the terminals of the plug is provided with a contact piece 8, which may be brought into contact with any one of the pieces of fuse metal. When it is desired to make this contact the piece of fuse metal is bent over the edge of the section 2 and then when the section is connected with the metallic piece 3 in its operative position and pushed to the limit of its inward movement, electrical connection is made with the contact piece 8 so as to connect the fuse metal in circuit with the metal piece 3. I prefer to provide the section 2 with openings 9 for the bent ends of the pieces of fuse metal. I also prefer to provide a piece 9^a

with one end in the opening 9, the piece 9^a overlapping the bent end of the fuse metal and projecting into the opening 4 so that this end engages the fuse metal inside of 5 the core of material 10. When the fuse is blown it will melt between this point and the end of the projection on the washer 6, the entire melting part being thus within the core. This prevents sparks of hot material 10 from being scattered about. The pieces 9^a cover the ends of the pieces of fuse metal and the openings in the solid material into which the pieces of fuse metal are embedded, and thus prevent the escape of any 15 products such as melted metal or gases from said openings when the fuse is blown. This construction therefore insures the prevention of the escape of metal or gases even though the entire fuse wire should be melted. The outer shell of porcelain or other material surrounding the core acts as a casing 20 for the core and where the pressure due to the blowing of the fuse is too great for the core to stand, this casing prevents the core from being cracked or otherwise injured when the fuse is blown.

The fuse metal may be placed in the core outside of the plug and then the entire core and fuse metal placed in the plug, although 30 I prefer to simply pour in the plug material after the fuse metal pieces are placed in the plug. The fuse metal pieces may be arranged in any desired manner, but I prefer to have the two pieces in opposite holes connected together, as shown in Fig. 5, there being an enlargement 5^a at the point where the fuse metal crosses the bottom of the plug, the two sections of fuse metal forming 40 the four fuses crossing each other substantially at right angles. When the fuse is constructed in this manner and the current through it is comparatively light but is still sufficient to blow the fuse, the fuse metal will melt intermediate the points where 6^a and 9^a contact the fuse metal. If the load is excessive, the entire fuse metal between these two points may melt, but in any event it will be seen that the part of the fuse metal that melts is entirely within the plug, and 50 that nothing can escape during the blowing of the fuse, the melting part of the fuse being sealed in the plug. The section 2 is preferably provided with the upstanding ribs 3^c which fit into the corresponding slots 55 in the section 1 and which hold the two sections against rotation and insure the second section being turned the proper amount to bring the fuse metal piece in contact with the contact piece 8.

60 It is of great importance to confine the portion of the fuse metal that melts to a portion thereof sealed in the plug and while I have shown one means of doing this, it might be accomplished in any other desired manner. In the construction shown, this re-

sult is secured by what consists in reality in reducing the cross sectional area of fuse metal for a portion of the length thereof sealed in the plug so that this portion cannot carry as much current as the portions outside of the plug. I have described in detail a particular construction, but it is of course evident that the parts may be varied in many particulars without departing from my invention as set out in the claims, and I do 75 not, therefore, limit myself to the particular construction illustrated.

I have illustrated in the drawings a plurality of pieces of fuse metal, but it is of course evident that that part of my invention relating to the embedding of the fuse metal in a core to prevent the production of gases and hot flying metal when the fuse blows, may be applied and used in connection with a single fuse. A fuse plug of this kind 85 with a single fuse is perfectly safe as when it is blown, no gas or hot flying metal will be produced, the point where the fuse is blown being sealed from the air and the oxygen thereof cannot act as is the case with 90 a fuse blown in the air.

I claim:

1. A fuse plug comprising two sections of insulating material, a metallic piece connected with one section and projecting therefrom, the other section being formed with a plurality of openings, a piece of fuse metal in each of said openings, a piece of conducting material at each end of each piece of fuse metal and engaging and overlapping the same, said piece of conducting material projecting part way into said openings, a core of solid material in each of said openings and surrounding a portion of each piece of fuse metal and a portion of each of said pieces of conducting material, and means for successively connecting said pieces of fuse metal in circuit.

2. A fuse plug comprising two sections of insulating material, a metallic piece connected with one section and projecting therefrom, the other section being formed with a plurality of openings, a piece of fuse metal in each of said openings, a contact piece at one end of the section containing the pieces of fuse metal and having projections thereon which project part way into said opening and engage the pieces of fuse metal therein, a conducting piece associated with each piece of fuse metal at the other end of said section, 110 said conducting pieces projecting part way into said openings and engaging said pieces of fuse metal therein, a contact piece connected with said metallic piece and adapted to be successively brought into electrical connection with said pieces of fuse metal and a core of solid material in each of said openings and surrounding a portion of said pieces of fuse metal and a portion of the projection on the contact at one end of the section 115 120 125 130

- containing the pieces of fuse metal and also surrounding a portion of the conducting piece at the other end thereof.
3. A fuse plug comprising a section of insulating material containing a plurality of pieces of fuse metal, pieces of conducting material at the ends of the pieces of fuse metal and engaging and overlapping the same, the body of the fuse metal and a portion of the overlapping pieces of conducting material embedded in solid material so that the melting of the fuse metal is confined to the portions thereof embedded in said solid material, said pieces of conducting material being attached to the section and projecting over the ends of the pieces of fuse metal so as to cover the same, and means for successively connecting said pieces of fuse metal in circuit.
- 20 4. A fuse plug comprising two relatively removable sections, one of said sections being provided with a plurality of openings, a piece of fuse metal in each of said openings, a piece of conducting material at each end of each piece of fuse metal and engaging and overlapping the same, said piece of conducting material projecting partway into said openings, a core of solid material in each of said openings and surrounding a portion of each piece of fuse metal, and a portion of each of said pieces of conducting material, and means for successively connecting said pieces of fuse metal in circuit.
5. A fuse plug comprising two separable and relatively movable sections, a plurality of pieces of fuse metal contained within one of said sections, an exposed contact at one end of the section containing the pieces of fuse metal and with which said pieces of fuse metal are electrically connected, a piece of conducting material overlapping the other end of each of said pieces of fuse metal, said pieces of fuse metal and the ends of said pieces of conducting material embedded in solid material, said pieces of conducting material projecting over the ends of the pieces of fuse metal and the material in which they are embedded so as to act as covers to cover the ends of said pieces of fuse metal to prevent the escape of particles of fuse metal produced when the fuse is blown, a separate contact piece connected with the other section and adapted to overlap one of the pieces of conducting material associated with the pieces of fuse metal, an outer metallic piece with which said separate contact piece is connected, and means for successively connecting said contact piece with said pieces of conducting material so as to successively connect said pieces of fuse metal in the circuit.
- 25 6. A fuse plug of the type described, comprising an insulating body having a separable portion, provided with a longitudinally extending channel; a fuse arranged in said channel having an end secured between an inner face of said body and the adjacent face of said portion; and barrier means extending across said end and the end of said channel for preventing the escape of particles of said fuse on blowing.
- In testimony whereof, I affix my signature in the presence of two witnesses this 29th day of March 1917.
- RALPH C. BRONSON.
